TELEPHONE INSTRUMENT BASE

Bronislaw Zapolski, Princeton, N.J., assignor to Sona-
phone Systems Incorporated, New York, N.Y.

Filed June 22, 1972, Ser. No. 265,309

Term of patent 14 years

Int. Cl. D14—03

U.S. Cl. D26—14 A

FIG 1

FIG. 2

FIG. 3

FIG. 4

FIG. 5

FIG. 6

FIG. 1 is a view in perspective of a telephone instrument base showing my new design.

FIG. 2 is a top plan view of a telephone instrument base shown in FIG. 1;

FIG. 3 is a right side view in elevation of a telephone instrument base shown in FIGS. 1 and 2;

FIG. 4 is a left side elevation of a telephone instrument base shown in FIGS. 1 and 2;

FIG. 5 is a front elevation of a telephone instrument base shown in FIGS. 1 and 2, and

FIG. 6 is a rear elevation of a telephone instrument base shown in FIGS. 1 and 2.

I claim:

The ornamental design for a telephone instrument base, as shown.
